UNITED STATES PATENT OFFICE.

JAMES ADAMS, OF CHICAGO, ILLINOIS.

ADJUSTABLE HOD-ELEVATOR.

SPECIFICATION forming part of Letters Patent No. 547,105, dated October 1, 1895.

Application filed February 23, 1895. Serial No. 539,369. (No model.)

To all whom it may concern:

Be it known that I, JAMES ADAMS, a citizen of the United States, residing at Chicago, in the county of Cook and State of Illinois, have invented certain new and useful Improvements 5 in Adjustable Hod-Elevators, of which the following is a specification.

This invention relates to improvements in elevators to be used in buildings for lifting 10 hods, wheelbarrows, &c.; and it consists in certain peculiarities of the construction, novel arrangement, and operation of the various parts thereof, as will be hereinafter more fully set forth and specifically claimed.

15 The objects of my invention are, first, to provide a hod-elevator which shall be simple and inexpensive in construction, strong and durable, yet effective in operation; second, such an elevator upon which two or more hods 20 and a wheelbarrow may be lifted at the same time, and, third, such an elevator the parts of which may be so adjusted as to pass between joists of different distances apart.

In order to enable others skilled in the art 25 to which my invention pertains to make and use the same, I will now proceed to describe it, referring to the accompanying drawings, in which—

Figure 1 is a perspective view of my elevator, showing it resting on the joists of a building and its parts so constructed and arranged as to elevate the greatest number of hods and a wheelbarrow or other device which may be placed upon the platform. Fig. 30 2 is a similar view of the device, showing it located on the joists of a building, the same being close together and the parts of the elevator being so constructed and arranged as to pass between the narrow spaces of said 35 joists. Fig. 3 is an enlarged central sectional view of a portion of the shaft upon which the sheaves and sprocket-wheel are mounted, showing the hub of the same provided with antifriction ball-bearings. Fig. 4 is a plan 40 sectional view of a portion of the driving-shaft and one of its bearings. Fig. 5 is a bottom plan view of the platform used in the construction shown in Fig. 1 of the drawings, showing it detached from the cage. Fig. 6 is 45 a detail perspective view of one of the rests for the hod. Fig. 7 is a perspective view of 50 a portion of a guide-rod, the securing devices

therefor, and a guide-arm for the platform. Fig. 8 is a perspective view of the upper portion of the cage. Fig. 9 is a similar view of 55 one of the lower cross-bars thereof; and Fig. 10 is an edge view of a portion of the platform, showing it made of two pieces hinged together.

Similar letters refer to like parts throughout the different views of the drawings.

A represents the main or supporting frame of my device, which is made of any suitable size, form, and material, but preferably of substantially the form shown in Figs. 1 and 65 2 of the drawings—that is, having four legs a, which are suitably braced or connected together at their lower portions by means of bars or rods a' and at their upper part by means of a transverse piece a², which supports the guide-rods a³, which are used for the purpose of guiding the platform and cage, as will be presently explained. In the top of the main or supporting frame A is fixed a shaft B, upon which is mounted a hub C, 70 which is provided near each of its ends with recesses c, in which are located antifriction-balls c', which balls are held slightly apart by means of a collar c², which is triangular in cross-section and encircles the shaft B, as 75 is shown. The balls c' are confined within the recesses c by means of the collars C', which are secured on the shaft B by means of set-screws c³ or otherwise. On the hub C are the grooved sheaves D and D', the latter 80 of which is much smaller in circumference than the former. The hub C is also provided with a sprocket-wheel E, over which passes a chain E' to engage either of the sprocket-wheels E² or E³, mounted on the driving-shaft 90 F, which shaft has its bearings about midway in the sides of the main or supporting frame and is provided at each of its ends with crank-handles f for turning the same. The legs a of the main or supporting frame are 95 provided about their middle with brackets or plates g, which are secured to the adjacent surfaces of the legs and are formed with recesses h to receive the lugs h' of the transverse pieces H, in which is formed recesses 100 h² for the reception and retention of antifriction-balls c', which are held slightly apart by means of a ring or collar c², encircling the shaft F. Passing over either one of the

sheaves D or D' is a cable I, one end of which is secured to the upper portion L of the elevator cage or frame L'. This upper part L is made of two pieces which overlap another piece, as shown in Fig. 8 of the drawings, and may be extended, when so desired, by removing the nut-screws l, which secure them together, when they may be adjusted to the desired length and again secured by means of the bolts or screws. The lower portion of the frame or cage L' is also provided with an extensible bar l', which is shown in Figs. 1 and 9 of the drawings, and it is obvious that the same may be extended by removing the connecting bolts or screws l and then replacing them when the pieces have been properly adjusted.

The upright pieces of the cage L' are secured at their lower ends to a rod m, located on the bottom of the platform M, which platform may be made of two pieces, as shown in Fig. 5 of the drawings, or of one piece, as illustrated in Fig. 2. To the lower surface of the platform are secured a number of straps n, to which are fastened the lower ends of the rods or bars n' of the cage, the other ends of which are secured to the uprights, as is clearly shown in Figs. 1 and 2 of the drawings. The platform M is also provided with other straps or pieces n², having eyes or openings in their adjacent ends through which is passed the rod m, thus hinging the two pieces of the platform together, as is apparent. To the upper portion L of the cage is secured plates o, provided with square openings for the reception and retention of the rectangular-shaped shank o' of the forked rests O for the hods o², which hods are of the ordinary kind and are provided with handles o³, which rest against the brackets o⁴ on the transverse extensible bar L³ of the cage, against which may rest another hod whose handle o³ rests on the platform M and is held in position by means of a socket-piece m' thereon. Near each end of the cross-bar a² of the main or supporting frame is secured guide-rods a³, which extend to the foundation of the building. These rods are held in a vertical and secure position by means of spikes e, which are driven in the joists e' and are formed at their free ends with semicircular hooks e², which partially encircle the rods a³. At proper points to the bottom of the platform and to the upper piece L of the cage is secured guide-pieces d, whose free ends are made in the form of a broken ring d' to encircle the guide-rods a³, yet will allow them to pass over the necks e³ of the spikes e', thus guiding the platform and cage of the elevator and preventing any wabbling thereof. As shown in Fig. 1 of the drawings, the chain E' is passed over the smaller sprocket-wheel E² on the driving-shaft F, and the cable I in said view is in position on the larger sheave D, while in Fig. 2 of the drawings the chain E' is shown on the larger sprocket-wheel E³, while the cable I is on the smaller sheave D', thus equalizing the power

required to elevate the different-weighted loads. When it is desired to place the chain E' from the smaller wheel E² to the larger one E³, the pieces in which the shaft F has its bearings may be moved from the lower recesses h in the brackets g to the upper ones, as is shown in Fig. 2 of the drawings. It is obvious that if it is desired to extend the size of the cage it may be readily done by removing the nut-screws l in the pieces l', L³, and L of the cage and reinserting them after the parts have been suitably adjusted. It is also apparent that by the use of my elevator I am enabled to hoist hods and brick between the joists, which are very close together, and when such is the case the rests o for the hods are placed in the position shown in Fig. 2, while when plenty of space is to be had the rests may be placed in the position shown in Fig. 1 of the drawings.

By reference to Figs. 3 and 4 of the drawings it will be seen and readily understood that by reason of the construction of the hub C and the piece H the balls will not be displaced by the removing of either of the shafts, for the reason that the collars c⁵ in the hub and those c⁶, which are screwed into the recesses c and h², respectively, will prevent any displacement of the balls.

It will be seen by reference to Figs. 1 and 2 of the drawings that the legs of the main frame are curved laterally or toward each other and at the ends of the frame, thus allowing the hods to be removed from the rests on the cage without obstruction. It will also be seen that the frame is contracted at its top, which permits of the use of a much shorter shaft B than would otherwise be required.

Having thus fully described my invention, what I claim as new, and desire to secure by Letters Patent, is—

1. The combination of a main frame with a shaft located in its top, a hub provided with anti-friction balls and loosely mounted on said shaft, a sprocket-wheel and grooved sheave on the said hub, a driving shaft having its bearings in the sides of the main frame and crank handles at each of its ends, a sprocket-wheel mounted on the driving shaft and having a chain to connect it with the wheel on the other shaft, a cable passing over the grooved sheave, an adjustable cage attached to each end of said cable and having adjustable rests for the hods, substantially as described.

2. The combination of the main frame A, with the recessed brackets or plates g, secured to its sides, the pieces H, having the recesses h, the balls c', therein, the rings c², between the balls and the lugs h', to fit in the recesses h, of the brackets, the driving shaft F, having its bearings in the pieces H, and provided at each of its ends with crank handles, the sprocket-wheels E², and E³, mounted on said shaft, the shaft B, located in the top of the main frame, the hub C, having the recesses c, and balls c', therein loosely mounted on the shaft B, the sprocket wheel E, and grooved

sheaves D, and D', on said hub, the chain E', uniting the sprocket wheels on the shafts B, and F, the cable I, to pass over the sheaves D, and D', and an adjustable or extensible cage 5 secured to each end of the cable, all constructed, arranged, and operating substantially as and for the purpose set forth.

3. The combination with a hoisting or lifting mechanism having guide rods, of the adjustable and extensible cage L', consisting of 10 the over-lapping cross-pieces L, L^g, and l', the adjustable platform M, secured to the lower

portion of the cage and having the guide-pieces d, with broken rings d', to encompass the guide rods, the plates o, secured to the 15 top of the cage and having openings therein, and the forked rests O, for the hods adapted to fit in said openings, substantially as described.
